UNITED STATES PATENT OFFICE

2,531,836

BOAT AWNING

Max W. Barr, Midland, Mich.

Application January 16, 1947, Serial No. 722,361

3 Claims. (Cl. 135—6)

1

This invention relates to improvements in awnings and especially those adapted to be used on boats of many classes.

An object of this invention is to provide an improved adjustable and removable awning mechanism adapted to be used on boats.

Another object of this invention is to provide means for adjusting the angularity of the cover components.

A further object of this invention is to provide means for securing the above mentioned adjusting means in selected positions.

A still further object of this invention is to provide improved anchoring means adapted to be used at the cover extremity.

Another object of this invention is to provide removable supporting means for the awning cover or body.

Other objects and features of novelty shall become apparent to those skilled in the art, or will be specifically pointed out in following the description of the preferred embodiment of the instant invention, illustrated in the accompanying drawings, wherein:

Figure 1 is an elevational side view of the preferred form of the instant invention;

Figure 2 is an elevational end view of the invention shown in Figure 1;

Figure 3 is an enlarged fragmentary sectional detail of construction showing the pivoted links forming part of the instant invention and taken substantially on the line 3—3 of Figure 2 and in the direction of the arrows;

Figure 4 is an enlarged fragmentary sectional view showing a detail of awning construction and taken substantially on the line 4—4 of Figure 2 and in the direction of the arrows;

Figure 5 is an enlarged fragmentary sectional detail showing an eyelet and securing means therefor and taken substantially on the line 5—5 of Figure 1 and in the direction of the arrows;

Figure 6 is a plan view of the preferred embodiment of the instant invention, and

Figure 7 is an enlarged sectional detail of construction showing particularly the base portion of the stand and taken substantially on the line 7—7 of Figure 2 and in the direction of the arrows.

Referring now in detail to the preferred embodiment of the instant invention, like reference characters are used throughout to indicate similar elements in the drawings.

A pair of stands 10 and 12 are provided to support a nylon, canvas or the like, cover 14.

2

It is here noted that two stands are provided, however, since each stand is identical only one will be described herein.

A base 16 having an annular, heavy bottom portion 18 is provided with a collar 20 integral with or secured thereto. A shaft 22 is adapted to be received in said collar 20 and may be held in frictional engagement therewith such as by a close fit or by conventional screw threads. At 10 the upper portion of said shaft 22 is a lug 24 adapted to receive eyelets 26 therearound. The said eyelet 26 is a conventional member of a tarpaulin or cover 14.

A substantially U-shaped frame member is provided under the said cover 14 and extends about the marginal edges thereof. Secured to one leg 28 of the said frame is a perch 30 having an aperture therethrough. A link 32 having apertures at each end thereof is received pivotally 15 in the said perch 30 at one end thereof and in a suitable perch 34 of a slideable collar 36 at the other end thereof. The said slideable collar 36 is received on the shaft 22 and has a tapered pin 38 attached by suitable chain means 40 thereto. 20 A plurality of apertures 42 are provided in the shaft 22 and are adapted to receive the said tapered pin 38 in selected positions in said shaft through the utility of said apertures. By this construction, the said collar 36 may be slidably 25 adjusted and latched in adjusted position on the said shaft 22. By adjustment of the collar 36 the leg 38 and consequently the web member 44 of said frame is relatively adjustable.

Oppositely disposed to the said perch 34 and 30 the said link 32 is an identical construction which is moved by the action of the said collar as described hereinabove.

As pointed out hereinbefore, there are provided two stands 10 and 12 and there are provided identical collar and linkage mechanisms on each stand. In order that the said cover or awning top 14 may be adjusted uniformly throughout, a connecting bar 46 is rigidly secured between each of the collars 36 which appear on the stands 10 and 12.

Secured to the corners of the said U-shaped frames are ropes or links 48 and 50. Suitable eyelets may be provided at the edges of the cover 14 through which the said rope 48 may extend. 50 Secured to the opposite ends of the said ropes are U-clamps 52 adapted to be anchored to the side of the boat 54. Obviously, the corners of the awning may be secured or anchored. When it is desirable to adjust the awning to another position other than shown, all that is

necessary is to slide the said clamps 52 transversely of the edge 56 of the boat and move the connecting bar 46 vertically. It is noted that since the clamps 52 may be slid parallel to the said side edge 56, the members 48 and 50 may be a single rigid strand such as wire and the like.

While there has been described herein but a single preferred embodiment of the instant invention, it is apparent that various changes including omissions and additions may be made herein without departing from the spirit of the invention. Accordingly, limitation is sought only in accordance with the scope of the following claims.

Having thus described my invention what is claimed as novel and improved is:

1. For use with a boat having sides and a bottom, spaced bases adapted to rest on the bottom of the boat, vertical stands attached to said bases, bosses slidably disposed on said stands, means to maintain said bosses in preselected vertical positions, substantially U-shaped frames including legs spaced from said stands, a web, and pitman links connecting said bosses and said legs, and a cover attached to said frames and a part of said cover between said frames supported by said vertical stands, said cover being secured to said legs thereby at least partially supporting said U-shaped frames on said stands.

2. For use with a boat having sides and a bottom, spaced bases adapted to rest on the bottom of the boat, vertical stands attached to said bases and having apertures therein, bosses slidably disposed on said stands, pins detachably secured in selected apertures to maintain said bosses in preselected vertical positions, substantially U-shaped frames including legs having their ends spaced from said stands and a web,

pitman links connecting said bosses and said legs, a cover attached to said legs and the part of said cover between the ends of said legs secured to said stands and supported by said vertical stands forming a hinge for said U-shaped members, said cover at least partially supporting said U-shaped frames, and flexible members each attached at one end to one of said U-shaped frame members and each having an adjustable clamp at the opposite end adapted to attach to the upper edges of the sides of a boat.

3. A canopy comprising a pair of vertical stands spaced from each other, bosses slidably disposed on said stands and having links pivoted thereto, a pair of substantially U-shaped frames, each having a web and a pair of legs extending therefrom, said links being pivoted to said legs, a cover disposed on said frames, the inner ends of the legs of one of the U-shaped frames being spaced from the inner ends of the legs of the other U-shaped frame, said cover being passed over said frames and arranged to cover the space between said inner ends of said legs and secured in this region to said stands forming a hinge point for said U-shaped frames, and means operatively connected with said bosses for maintaining said bosses in a selected position on said stands.

MAX W. BARR.
